UNITED STATES PATENT OFFICE.

BURNETT THOMAS WASHINGTON, OF WILLIAMSON, WEST VIRGINIA.

CAR-TRUCK SIDE FRAME.

Application filed November 5, 1925. Serial No. 67,039.

The present invention relates to the construction of the side frame for a car truck which admits of the supporting of a jack upon a tie when it is required to elevate the frame to replace a worn bearing, or for other purpose irrespective of the position of the truck with reference to the jack.

A side frame of usual construction requires the truck to be positioned, so that the journal box is in vertical line with a tie, to admit of placing the jack upon a tie when it is required to lift the frame to replace a bearing, or for other purpose.

In accordance with the present invention the ends of a side frame of a car truck have straight longitudinal under surfaces to admit of the jack engaging the same at different points in the length of the surface while the jack is supported upon a tie, thereby obviating the necessity of moving the car to place the jack so that it may engage both a tie and the end of the frame when the latter is required to be elevated.

While the drawings illustrate the preferred embodiment of the invention, it is to be understood that in adapting the means to meet specific needs and requirements, the design may be varied and such other changes in the many details of construction may be resorted to within the scope of the invention as claimed, without departing from the spirit thereof.

For a full understanding of the invention and the merits thereof, reference is to be had to the following description and the drawings hereto attached, in which,—

Figure 1 is a side view of a car truck provided with a frame embodying the invention,

Figure 2 is a plan view of the side frame, and

Figure 3 is an enlarged sectional view on the line 3—3 of Figure 1 looking in the direction of the arrows.

Corresponding and like parts are referred to in the following description and indicated in the several views of the drawings by like reference characters.

The side frame is of the general diamond shape and comprises an upper chordal member 1, a lower chordal member 2, side columns 3 connecting the chordal members and end journal boxes 4, the several parts being preferably of integral formation, although

it is not essential as the frame and its component parts may be of any determinate construction. The numeral 5 designates the usual bolster and 6 the bolster supporting springs resting upon the plank 7. Studs 8 project inwardly from the upper curved member 1 adjacent the upper ends of the bolster side columns 3 and have openings to receive the hooked ends 9 of brake hanger bolts 10 which are supported in the member 1.

A web 11 reinforces the joint formed between each of the journal boxes 4 and the adjacent end of the frame and these webs are disposed midway between the sides of the frame, as shown most clearly in Figure 2. An extension 12 projects outwardly from the lower side of each of the journal boxes 4 and a web 13 connects each of the extensions 12 with the outer side of the journal box. A straight surface 14 is provided at each end of the frame in line with the lower side of the journal box and this is of such longitudinal extent as to rest upon a jack positioned upon a cross tie of the track when it is required to elevate the frame to replace a worn bearing or for any desired purpose.

Having thus described the invention, what I claim is:

1. A car truck side frame comprising upper and lower members and intermediate connecting bolster side columns, the upper member having inwardly disposed studs and brake hanger bolts supported in said member and having their inner ends of hook form to enter openings in the said studs.

2. A car truck side frame comprising upper and lower members, intermediate connecting bolster side columns, and end journal boxes, the lower member having its end portions extending beyond the outer sides of the journal boxes in line with their bottom surfaces to provide extended surfaces for a lifting jack when supported upon a cross tie, webs between the outer sides of the journal boxes and the end extensions of the lower frame member, and other webs between the tops of the journal boxes and upper frame member.

In testimony whereof I affix my signature.

BURNETT THOMAS WASHINGTON. [L.S.]
